DESIGN FOR A PARING AND PEELING KNIFE

Thomas Carangi, West Pittsburgh, Pa.

Application February 18, 1936, Serial No. 61,227

Term of patent 7 years

To all whom it may concern:

Be it known that I, Thomas Carangi, a citizen of the United States, residing at West Pittsburgh, in the county of Lawrence and the State of Pennsylvania (Box 192), have invented a new, original, and ornamental Design for a Paring and Peeling Knife, of which the following is a specification, reference being had to the accompanying drawing, forming a part thereof.

I claim:

The ornamental design for a paring and peeling knife, substantially as shown.

THOMAS CARANGI.
